UNITED STATES PATENT OFFICE.

JAMES E. PELLOW, OF SIERRA CITY, CALIFORNIA.

LEAF-TURNER.

SPECIFICATION forming part of Letters Patent No. 439,550, dated October 28, 1890.

Application filed November 5, 1889. Serial No. 329,300. (No model.)

To all whom it may concern:

Be it known that I, JAMES E. PELLOW, of Sierra City, in the county of Sierra and State of California, have invented a new and Improved Music-Leaf Turner, of which the following is a full, clear, and exact description.

The object of the invention is to provide a new and improved music-leaf turner, which is simple and durable in construction and very effective in operation, serving to quickly turn the leaves successively from right to left or from left to right in case a repetition of the music is required.

The invention consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a front view of the improvement, the cover of the shaft-box being removed. Fig. 2 is an enlarged transverse section of the same on the line xx of Figs. 1 and 3. Fig. 3 is a sectional plan view of the same on the line yy of Figs. 1 and 2. Fig. 4 is an enlarged transverse section of part of the improvement on the line zz of Fig. 1. Fig. 5 is an enlarged face view of the box-cover. Fig. 6 is a front view of a modified form of the improvement. Fig. 7 is an inverted plan view of the same, and Fig. 8 is an end view of the same.

The music-leaf turner A consists, principally, of a series of shafts, each provided with an arm adapted to hold the leaf to be turned, a spring-actuated mechanism connected with each arm for turning the latter after a button is pressed, and a locking device releases the said mechanism, as shown in Figs. 1 to 5, inclusive. The improved music-leaf turner A is provided with a back B, to the lower end of which is pivoted an extension-plate C, against which press springs D to force the extension-plate in line with the back B. The extension-plate C may be locked at any desired angle in relation to the back plate B by means of a locking device E. The latter is provided with a slotted arm E', pivoted to a lug E², secured on the back plate B, as is plainly shown in Figs. 1 and 4. Through the

slot of the arm E' extends a notched segment E⁴, secured on the extension-plate C, and adapted to engage by one of its notches the lower end of the slot in the arm E'. A spring E³, secured on the back plate B, presses against the top of the arm E', so that the latter is held in firm contact with the respective notch of the segment E⁴. By moving the plate C upward the arm E' engages one of the notches in the segmental plate E⁴, so that the said plate C is held at an angle to the back plate B. The latter usually rests in an inclined position against the piano, and as the extension-plate C can be adjusted to any desired angle it rests horizontally on the offset of the music-holder on the piano.

In the middle of the back B is held a box F, provided with a cover F', secured to the box in any suitable manner. Inside of the box F are mounted, to turn in suitable bearings, the upwardly-extending shafts G, each of which passes through the upper end of the box and carries on its outer end a hollow arm G', in which is held to slide a rod G², adapted to be secured in any desired place in the arm G' by a set-screw G³. On the outer end of each rod G² is held a hollow arm G⁴, extending at right angles to the rod G², and in which is held to slide upward a rod G⁵, adapted to be secured in place in the said hollow arm G⁴ by a set-screw G⁶. Each of the rods G⁵ carries one, two, or more spring-clasps G⁷, of any improved construction, and adapted to clasp the outer end of the leaf H to be turned.

The leaves H are held on the covers H' of the book of music, and the said covers rest against the upper part of the back plate B and are held on the same by plates I, each pivotally connected with the upper end of a lever I', fulcrumed to a post I², secured to the back plate B. The lower end of the lever I' has a finger-piece I³, against the under side of which presses a spring I⁴, so as to hold the plate I firmly in contact with the respective cover H'. When the performer presses on the finger-piece I³, the plate I is lifted off of the cover H', and the book can be conveniently removed from the back plate. Both plates I are arranged near the outer ends of the back plate B, as shown in Fig. 1.

The lower edges of the covers H' are adapted to rest on offsets J², secured to arms J and J', ex-

tending in opposite directions from each other, being pivoted at J^3 to the back plate B. The inner ends of the arms J and J' are provided with segmental gear-wheels J^4 and J^5 , respectively, said gear-wheels being in mesh with each other. A spring J^6 connects the arms J and J' with each other, serving to hold the arms J and J' downward, said arms resting at their outer ends against the posts I² previously mentioned. Arms J and J' when raised in a vertical position serve to hold sheet-music that is not bound in book form. In raising the arms J and J' the spring J^6 , after passing the center of the segmental gear-wheels, draws the offsets of the arms J and J' closely together. By placing the margin of the sheet of music between them and pressing the right arm to the left a spring-catch from behind the main plate B holds the right arm J in place, and the spring at the bottom, drawing them together, holds the sheet of music as firm as though bound in books. These arms serve two purposes—when down, as a rest for the bottom of the book; when raised, to hold sheet-music not bound in book form.

On each of the shafts G, inside of the box F, is secured a roller K, having in its periphery a spiral groove K', engaged by a pin L', projecting from a rod L, mounted to slide in suitable bearings parallel to the shaft G. On each rod L is secured a knob L², which projects through the slot F², formed in the cover F' of the box F, so that the operator can conveniently move the rod L up or down by taking hold of the knob L². On each rod L is secured a transversely-extending arm N, the rear end of which is engaged by one end of a coil-spring O, secured in the box F. When the arm L is moved downward, the spring O is put under tension, and has the tendency to draw the rod L upward. The upper end of the rod is slightly beveled at L³, (see Fig. 2,) and this upper end is adapted to be engaged by the bent end P' of a lever P, fulcrumed on a post P², erected in the box F. The lower end of each lever P is provided with a finger-piece or knob P³, extending through an aperture F³, formed in the cover F' of the box F. Against the lower end of each lever P presses a spring Q, secured in the box F and serving to hold the bent end P' of the lever P in contact with the rod L. When the latter is in a lowermost position, as shown in Fig. 2, the bent end P' of the spring-pressed lever P engages the upper end of the rod L, thus locking the latter in place against the compressed spring O.

On the extension-plate C is secured a hollow offset C', on which is held to slide longitudinally a rod R, provided with a number of spring-clamps S, of any suitable construction.

The operation is as follows: When the performer desires to use the music-leaf turner, he places the back B, with its extension-plate C on the music-rack of the piano, as previously described. He then places the book containing the music on the back plate B, so

that the lower edges of the book-cover rest on the offsets of the arms J and J', the performer having previously pressed on the finger-pieces I³ to lift the plates I upward to permit the entrance of the covers on the back plate B. The moment the operator releases the finger-piece I³ the springs I⁴ firmly press the plates I in contact with the covers H', thus holding the book firmly in place on the music-turner. The several leaves H, held in the covers H', are each fastened at one end to a spring-clamp G⁷ on one of the rods G⁵. The several leaves being thus fastened to the several rods G⁵, the operator then turns the leaves I by means of the arms G', carrying the rods G⁵ and the clamps G⁷ to the right, into the position shown in Fig. 1. By this movement of the arms G' each shaft G is turned, therefore by turning its roller K, which by its spiral groove K' moves the respective rod L into a lowermost position, as the pin L' of the said rod travels in the spiral groove. This downward movement of each rod L compresses the respective spring O, and when the rod L has reached its lowermost position the upper end P' of the lever P engages the upper end of the respective rod L, and locks the latter in place. As the rod L is locked in place the roller K and the respective shaft G are similarly locked by the locking of the rod L, and consequently the arms G' are locked in place to the right, holding the leaves H on the right cover of the book. The arms G' of the several shafts G are arranged one above the other, as shown in Fig. 1, so as not to interfere with each other in operating the music-leaf turner. When the performer has played one side of the first leaf H and desires to turn the latter, he presses on the knob P³ of the respective shaft G, carrying the arm G', connected by its rod G⁵ and the clamps G⁷ with the first leaf. The moment the performer presses the lever P, the bent end P' is disengaged from the upper end of the rod L, and the latter by the action of the spring O is turned upward, whereby the pin L' on the said rod L, traveling in the groove K', turns the roller K. The turning of the latter causes the turning of the shaft G, so that the rod G' swings from the right to the left, and the leaf H is consequently carried to the left-hand cover of the book—that is, the leaf has been turned. When the performer has reached the bottom of the first side of the next following page, he presses on the knob P³, belonging to second device, so that the second roller K is turned and with it the shaft G, whereby the arm G' of the latter swings from the right to the left and carries the second leaf over. In a similar manner the several leaves can be turned. When the performer desires to read the music he takes hold of the knobs L² successively and presses the same downward, so that the rods L are moved downward, and, by their pins L' turn the respective rollers K, which in turn, by being secured on the shafts G, swing the arms G' from the left back

to the right in the position shown in Fig. 1. When the rods L are moved downward into their lowermost position, the bent ends P' of the levers P can pass over the ends of the 5 rods L to lock the same in place, as previously described. The above-described operation is then repeated.

In the modification shown in Figs. 6 to 8 the shaft G is mounted on a plate U, held on 10 the frame B, and instead of carrying a grooved roller K is provided with a gear-wheel T, meshing into a gear-wheel T', provided with a handle T², standing in its normal position upright and serving for turning the said 15 gear-wheel T' from right to left and imparting rotary motion to the gear-wheel T from left to right, and consequently to the shaft G, in order to set the device. The gear-wheel T also meshes into a rack T³ opposite the 20 gear-wheel T, the said rack being mounted to slide in suitable bearings on the plate U. A spring T⁴ is coiled in the said rack and presses onto the same from left to right. One outer end of the rack T³ projects beyond 25 one of the bearings, and is adapted, when the device is set, to butt against an arm V, secured on a spring V', held on the rear side of the plate U, the said arm passing through a slot in the said plate U to the 30 front. A knob or button V² is secured on the outer end of the arm V and serves to press the latter rearward against the tension of the spring V'. An aperture V³ of about 35 the size of the end of the rack T³ is formed in the arm V above the contacting point of the rack T³ with the arm V, so that when the latter is pressed rearward the aperture V³ comes in line with the end of the rack T³, and the latter is permitted to slide from the 40 left to the right, this movement being effected by the compressed spring T⁴.

The operation is as follows: When the performer desires to use the music-leaf turner, he fastens the music-leaf to the clamp G⁷ in 45 the manner previously described and then takes hold of the handle T², which stands then in upright position, and swings it to the left, whereby the shaft G is turned from left to right and the leaf carried to the right 50 side of the book or stand. The movement of the handle T² causes the gear-wheel T to move the rack T³ from right to left until the projecting end of the rack is disengaged from the aperture V³ in the arm V and the latter 55 moves outwardly by the force of the spring V', so that when the operator releases the handle T² the end of the rack butts against the arm V below the aperture V³. The rack, as well as the other parts, are now locked in 60 place. When the operator now desires to turn the leaf over while playing, he presses slightly on the button V² of the arm V, whereby the latter is moved rearward and the aperture V³ registers with the end of the rack T³, 65 whereby the compressed spring T⁴ forces the rack to the right, the end of the rack passing through the aperture V³. This movement of

the rack turns the gear-wheels T and T', and consequently the shaft G, from right to left, whereby the arm G' moves the leaf in the 70 same direction—that is, turns the leaf.

It is understood that any desired number of devices above described may be placed on the plate U, one above the other, the number corresponding to the number of leaves to 75 be turned—that is, each leaf has its separate device and is operated on independently of the other and in the manner above described.

It is understood that when several devices are used they are set and operated on one 80 after the other in regular order.

I do not limit myself to the exact construction shown, as it is obvious that the details may be varied within reasonable limits without departing from the spirit of my invention. 85

Having thus fully described my invention, I claim as new and desire to secure by Letters Patent—

1. In a music-leaf turner, the combination, 90 with one or more shafts, each carrying an arm adapted to hold the free end of the leaf to be turned, of a spring-actuated roller for turning the said shaft, a locking device for locking the said shaft and mechanism in 95 place, and means, substantially as described, for setting the said mechanism, substantially as shown and described.

2. In a music-leaf turner, the combination, 100 with a shaft mounted to turn, and a leaf-turning arm secured at right angles to the said shaft, of a roller secured on the said shaft and provided with a spiral groove, and a rod mounted to slide and carrying a pin engaging the said spiral groove, substantially as shown 105 and described.

3. In a music-leaf turner, the combination, 110 with a shaft mounted to turn, and a leaf-turning arm secured at right angles to the said shaft, of a roller secured on the said shaft and provided with a spiral groove, a rod mounted to slide and carrying a pin engaging the said spiral groove, and a spring acting on the said rod, substantially as shown and described.

4. In a music-leaf turner, the combination, 115 with a shaft mounted to turn, and a leaf-turning arm secured at right angles to the said shaft, of a roller secured on the said shaft and provided with a spiral groove, a rod mounted to slide and carrying a pin engaging 120 the said spiral groove, a spring acting on the said rod, and a spring-pressed locking-lever serving to lock the said rod in place when the said spring is compressed, substantially as shown and described. 125

5. In a music-leaf turner, the combination, 130 with a spring-actuated revolving roller, of a shaft secured to said roller and connected with the leaf, and a locking device for holding the roller in place, substantially as shown and described.

6. In a music-leaf turner, the combination, 135 with a spring-actuated revolving roller, of a shaft secured to said roller and connected

with the leaf, and a spring-actuated locking device for holding the roller in place, substantially as shown and described.

7. In a music-leaf turner, the combination, 5 with a back plate, of an extension-plate hinged on the lower end of the said back plate, and a device, substantially as described, for locking the said extension-plate in place at any desired angle relative to the said back 10 plate, substantially as shown and described.

8. In a music-leaf turner, the combination, 15 with a back plate, of an extension-plate hinged on the lower end of the said back plate, a device, substantially as described, for locking the said extension-plate in place at any desired angle relative to the said back plate, and a spring pressing on the said extension-plate, substantially as shown and described.

9. In a music-leaf turner, the combination, 20 with a back plate, of two arms pivoted to said back plate, said arms being constructed and arranged substantially as described, so that when in a horizontal position they are adapted to serve as a rest, and when in a 25 vertical position act as a clamp, as set forth.

10. In a music-leaf turner, the combination, 30 with a back plate, of two arms pivoted on the said back plate and extending in opposite directions from each other, segmental gear-wheels formed on the said arms and held in mesh with each other, and a spring connecting the said arms with each other, substantially as shown and described.

JAS. E. PELLOW.
